DESIGN FOR A COMBINED SOAP BOWL AND HOLDER

Leo Bertisch, Cedarhurst, N. Y.

Application September 30, 1944, Serial No. 115,544

Term of patent 14 years

(Cl. D86—10)

To all whom it may concern:

Be it known that I, Leo Bertisch, a citizen of the United States, residing at Cedarhurst, L. I., in the county of Nassau and State of New York, have invented a new, original, and ornamental Design for a Combined Soap Bowl and Holder, of which the following is a specification, reference being had to the accompanying drawing, forming part thereof.

In the drawing:

Fig. 1 is a front elevational view of a combined soap bowl and holder, showing my new design;

Fig. 2 is a right side elevational view thereof;

Fig. 3 is a top plan view; and

Fig. 4 is a rear elevational view thereof.

I claim:

The ornamental design for a combined soap bowl and holder, substantially as shown.

LEO BERTISCH.
